(57) **CLAIM**

The ornamental design for a shoe, as shown and described.

DESCRIPTION

FIG. 1 is a front bottom perspective view of a shoe showing my new design;

FIG. 2 is a bottom view thereof; and,

FIG. 3 is a rear bottom perspective view thereof.

The broken lines immediately adjacent to the shaded area define the bounds of the claimed design and form no part thereof. The bowtie-shaped broken line and the unshaded region therein form no part of the claimed design. The ten small broken line circles represent tread features that form no part of the claimed design. The broken lines depicting the remainder of the shoe form no part of the claimed design.
